(57) **CLAIM**

The ornamental design for a rotatable handheld accessory for holding objects, as shown and described.

DESCRIPTION

FIG. 1 is a perspective view of a rotatable handheld accessory for holding objects;

FIG. 2 is another top perspective view of the rotatable handheld accessory illustrated in FIG. 1 shown in an alternate position.

FIG. 3 is a top view of the rotatable handheld accessory illustrated in FIG. 1;

FIG. 4 is a right side elevation view of the rotatable handheld accessory illustrated in FIG. 1;

FIG. 5 is a left side elevation view of the rotatable handheld accessory illustrated in FIG. 1;

FIG. 6 is a bottom view of the rotatable handheld accessory illustrated in FIG. 1;

FIG. 7 is a front view of the rotatable handheld accessory illustrated in FIG. 1; and,

FIG. 8 is a rear view of the rotatable handheld accessory illustrated in FIG. 1.

The broken line showing of the rotatable handheld accessory for holding objects is for the purpose of illustrating portions of the article and forms no part of the claimed design.

1 Claim, 4 Drawing Sheets
